UNITED STATES PATENT OFFICE.

ARTHUR MORT, OF LINCOLN, ENGLAND.

DROP-HAMMER.

1,309,298.

Specification of Letters Patent.

Patented July 8, 1919.

Application filed September 5, 1918. Serial No. 252,794.

To all whom it may concern:

Be it known that I, ARTHUR MORT, a subject of the King of Great Britain and Ireland, and resident of Craig-y-den, Yarboro' 5 Road, Lincoln, Lincolnshire, England, have invented certain new and useful Improvements in Drop-Hammers, of which the following is a full, clear, and exact specification.

10 This invention relates to drop hammers the tup of which is adapted to be lifted by mechanical means. The invention consists in the adaptation to such a hammer of an epicyclic gear or sun and planet train of 15 wheels.

One embodiment of the invention is illustrated in the accompanying drawings in which Figure 1 is a front view and Fig. 2 an end view of a drop hammer showing, by 20 way of example, the adaptation of an epicyclic gear thereto. Fig. 3 is a detail view of the overhead gearing to enlarged scale and Fig. 4 an end view of the gear elements.

25 Referring to the drawings, surmounting the superstructure of the drop hammer is a driving shaft A fitted with a fly-wheel A' and carrying a driving pulley B or the like whereby the shaft may be driven from 30 a suitable source of power. On the shaft A is mounted an epicyclic gear inclosed within a gear case D forming an oil bath, said gear comprising a sun pinion E keyed to the shaft A, two or more planet pinions F adapt- 35 ed to be driven thereby and an internal gear element G integral with the brake wheel H and fitted with a band brake H', said internal gear element G being meshed by said pinions F. The planet wheels F are mount- 40 ed on pins I to which is secured the boss J of lifting arms K for raising the hammer tup, a guide pulley L being mounted on the shaft A between the lifting arms K for guiding the ropes or the like connecting 45 the said lifting arms and the hammer tup.

With this arrangement when the brake is free the sun pinion E and the brake wheel

H revolve, and the planet pinions F operatively connected with the lifting arms K and thus with the ropes or the like remain stationary. When the brake is applied, the 50 brake wheel H ceases to revolve or revolves only slowly and the planet pinions F revolve, carrying with them the lifting arms K, thereby lifting the hammer tup. On sub- 55 sequent release of the brake the hammer tup falls by gravity. A high speed is thus obtained for the driving shaft A, an intermediate speed for the brake wheel H and a slow 60 speed for lifting the hammer head.

As will be understood, the arrangement of the epicyclic gear may be modified without departure from the invention.

What I claim is:

1. In a drop hammer in combination with 65 a hammer tup and lifting arms for raising the tup, means for actuating said lifting arms and an epicyclic gear controlling the actuation of said lifting arms by said means, substantially as and for the purpose set 70 forth.

2. In a drop hammer in combination with a hammer tup and lifting arms for raising the tup, means for actuating said lifting arms, and an epicyclic gear interposed be- 75 tween said lifting arms and said means, whereby to control said lifting arms, sub- stantially as and for the purpose set forth.

3. In a drop hammer in combination with a hammer tup and lifting arms for raising 80 the tup, means for actuating said lifting arms, and an epicyclic gear controlling the actuation of said lifting arms, said lifting arms being in pin-joint connection with said gear, substantially as and for the purpose 85 set forth.

In testimony whereof I have signed my name to this specification in the presence of two subscribing witnesses.

ARTHUR MORT.

Witnesses:

THOS. H. COOK,
C. M. HITCH.
